PORATION OF NEW YORK.

AMPLIFYING SYSTEM.

Application filed November 13, 1925. Serial No. 68,784.

This invention relates to amplifying systems, and more particularly to networks used to couple two or more space discharge amplifiers in tandem.

5 An object of the invention is to secure a uniform voltage transformation of waves within a prescribed substantial range of frequencies.

Another object is to increase the over-all 10 amplification of a space discharge amplifier to the maximum degree consistent with uniform amplification throughout a prescribed band of frequencies.

A further object is to provide a coupling 15 circuit for multi-stage amplifiers in which are combined the properties of voltage transformation and of broad-band frequency selectivity.

A feature of the invention lies in the use 20 of a pair of coupled tuned circuits to constitute a wave transforming network and in the manner of proportioning the network coefficients to secure the desired objects.

The properties of a network comprising 25 two coupled tuned circuits are well known in a general way, one of the most familiar characteristics being the double resonance occurring at frequencies separated by an interval which is determined by the coefficient of coupling. Transmission through a network 30 of this type is characterized by large output currents or voltages at the two resonance frequencies and by a diminution of the output at frequencies therebetween. The diminution of output at the intermediate frequencies may 35 be so great as to practically extinguish waves of these frequencies, and this has heretofore caused the use of simple coupled circuits to be restricted to the selective transmission of very narrow wave bands, under which condition the two resonance frequencies are practically merged together.

By proportioning the coefficients of the coupling circuit in accordance with the present invention, it is found that all waves of 45 frequencies within a substantially wide range, limited by the resonance frequencies, can be transformed in a substantially uniform degree, and transmitted with little loss of energy, while waves outside of these limits are 50 strongly attenuated.

The nature of the invention and manner of its application will be fully understood by referring to the following detailed descrip-

tion and to the accompanying drawing forming a part thereof, in which

55 Fig. 1 shows in conventional schematic the embodiment of the invention in multi-stage amplifier circuit;

Fig. 2 is a simplified schematic corresponding to Fig. 1; and

60 Figs. 3, 4 and 5 are characteristic curves to illustrate the principle and the operation of the invention.

The amplifier system of Fig. 1 comprises space discharge amplifiers 1 and 2, of the 65 customary three-electrode type, connected in tandem arrangement between a wave source 3 and a load circuit 4, which is conventionally indicated. The coupling circuit comprises an anti-resonant circuit 5 connected between 70 points A and B in the anode circuit of amplifier 1, and a second anti-resonant circuit 6 inductively coupled to circuit 5 and connected between terminals C and D in the input circuit of amplifier 2. Circuits 5 and 6 are pro- 75 portioned to resonate at substantially the same resonance frequency. A non-inductive resistance 7 is also connected between terminals C and D to form a terminating impedance for the coupling circuit. This resistance may in 80 certain cases be constituted, at least in part, by the space resistance between the grid and cathode of the succeeding amplifier. The coefficients of the capacity elements in anti-resonant circuits 5 and 6 are denoted by C_1 85 and C_2 , respectively, and the inductances by L_1 and L_2 . Capacity C_2 may be provided by a separate condenser, but in the preferred arrangement the tuned circuit 6 is so proportioned that resonance is effected with the self 90 capacity of the inductance coil together with the input capacity of amplifier 2.

The relationships involved in proportioning the elements of the coupled circuits to secure resonance at specified frequencies, and 95 to provide a definite value of voltage transformation ratio are well known. These relationships, however, are insufficient to determine the actual values of the individual impedance coefficients, and if the undetermined 100 constants are chosen at random the resulting circuit is likely to have a quite unsatisfactory transmission characteristic.

The method of designing the coupling circuit so that it conforms not only to the re- 105 quirements relating to the resonance frequen-

cies and to the voltage transformation ratio, but also to requirements of transmission efficiency, is explained in the following mathematical analysis.

5 For the purpose of the analysis, the essential parts of Fig. 1 are shown in a simplified schematic form in Fig. 2. In this schematic, the sending end impedance R_1 corresponds to the space path resistance of amplifier 1, 10 and the electromotive force E_1 of the wave source is the repeated electromotive force corresponding to the wave impressed on the amplifier. The transformer formed by coupled inductances L_1 and L_2 is replaced by the well 15 known equivalent T network, the inductances of the arms of which are designated in terms of the self inductances L_1 and L_2 and the mutual inductance M . Resistance R_2 in Figure 2 corresponds to the terminating resistance 7. The only element of amplifier 2 that 20 enters into the circuit is its input capacity, and this is assumed to be included in capacity C_2 .

A method of computing the output currents 25 and voltages in a transmission circuit such as is shown in Fig. 2 is described fully by O. J. Zobel, "Transmission characteristics of electric wave filters", Bell System Technical Journal, Volume III, No. 4, October 1924, page 30 567. In accordance with this method it is necessary first to determine certain parameters of the coupling circuit, known as the "image" parameters, which comprise image impedances corresponding to each pair of terminals, and the image transfer or propagation constant. By means of these parameters and the terminating impedances of the system, the output currents and voltages may be computed, suitable formulae for this computation 35 being given by equations 69 and 70 in the article by Zobel mentioned above.

The advantages of this method lie in the comparative ease with which the image parameters of a network composed of substantially pure reactances can be computed, and in the fact that the dominating characteristics of the system can be arrived at by a study of the image parameters alone. A property of the image parameters that is of great help in 40 making qualitative analysis of a circuit is this, that when the image impedance at either end is equal to the terminating impedance there is no reflection at that end, and, furthermore, the disparity of the two impedances 45 is a measure of the amount of reflection that takes place.

The transfer constant is a measure of the ratio of the input and the output currents and voltages when the condition holds that the 50 terminating impedances are respectively equal to the image impedances. Under this condition it is equal to the natural logarithm of the current or the voltage ratio corrected to correspond to unity transformation ratio in 55 the network.

Let W_a and W_b denote the image impedances of the coupling circuit of Figs. 1 and 2 at the terminals AB and CD respectively, and let T be the image transfer constant of the circuit. Then, as explained in the reference above, 70 W_a , W_b and T may be computed from the open circuit impedances X_a and X_b of the coupling circuit, measured at terminals AB and CD respectively, and the corresponding short circuit impedances Y_a and Y_b . These quantities are related by the following equations: 75

$$\left. \begin{aligned} \operatorname{Tanh} T &= \sqrt{\frac{Y_a}{X_a}} = \sqrt{\frac{Y_b}{X_b}}, \\ W_a &= \sqrt{X_a Y_a}, \\ W_b &= \sqrt{X_b Y_b}. \end{aligned} \right\} \quad (1) \quad 80$$

The computation of the open circuit and the short circuit impedances is a straight forward algebraic process, but if an attempt is made to take into account the resistance of the reactive elements, the resulting expressions are likely to be very cumbersome. In the coupling circuit of this invention, as in practically all selective circuits, the reactive elements are so constructed as to have a very small resistance in comparison with their reactances, and it is practicable to assume that the resistances are zero. 85

Assuming that the elements of the coupling circuit are pure reactances, and bearing in mind that the two anti-resonant circuits are resonant at the same frequency, the following equations, by which the image impedances 90 are expressed in terms of the wave frequency f' may be derived with the help of Equation 1:

$$W_a^2 = \frac{1}{4\pi^2 f'^2 C_1^2} \frac{1-k^2}{\left(1-k-\frac{f_0^2}{f'^2}\right)\left(\frac{f_0^2}{f'^2}-1-k\right)}, \quad (2) \quad 105$$

and

$$W_b = W_a \times \frac{C_1}{C_2}. \quad (3) \quad 110$$

In the above equations, k is the coefficient of coupling between inductances L_1 and L_2 , and f_0 denotes the common resonance frequency of the two anti-resonant circuits.

The right hand side of Equation 2 may have 115 a real or an imaginary value but may not be complex, from which it follows that W_a is either a pure resistance or a pure reactance. An examination of the expression shows that W_a is resistive at all frequencies between two 120 limiting values f_1 and f_2 , given by the equations

$$\left. \begin{aligned} f_1 &= \frac{f_0}{\sqrt{1+k}}, \\ f_2 &= \frac{f_0}{\sqrt{1-k}}. \end{aligned} \right\} \quad (4) \quad 125$$

At the limiting frequencies W_a is infinite and at frequencies outside of the limits the imped- 130

ance is reactive. W_b bears a constant numerical ratio to W_a .

Between the limits f_1 and f_2 the image impedances are resistive because of the fact 5 that the open circuit and short circuit impedances are reactances of opposite sign and are therefore expressed by imaginary quantities of opposite sign the product of which is positive. It follows that the ratio of the 10 two impedances is negative throughout this frequency range and hence that the transfer constant is imaginary. Conversely, the transfer constant is a real quantity at frequencies outside the range between frequencies f_1 15 and f_2 .

The coupling network thus possesses characteristics similar to those of a broad band filter. Throughout a range of frequencies limited by f_1 and f_2 , the waves are not attenuated but are merely shifted in phase, 20 while at other frequencies they are strongly attenuated. These characteristics are, however, modified to a greater or less extent by reflections at the terminals when the terminating impedances are not equal at all frequencies to the image impedances. 25

In the design of coupled tuned circuits it has not hitherto been the practice to take the terminal reflection losses into account, and in 30 consequence it has not been possible to secure the uniform amplification of a selected band of frequencies, except in cases where the selected band is very narrow in proportion to its mean frequency. In the coupling circuit of 35 the invention the reflection effects are reduced to an unimportant amount by making the image impedances substantially equal to the terminating impedances throughout the greater part of free transmission range.

40 Equations 2, 3 and 4 suffice to determine the design in accordance with the following procedure:

The band of waves it is desired to transmit fixes the frequencies f_1 and f_2 , from which 45 the common resonance frequency f_0 and the coefficient of coupling k may be found by means of Equations 4. The next step is to determine the capacity C_1 of the primary tuned circuit by means of Equation 2, the 50 condition being specified that W_a is equal to the internal resistance R_1 of amplifier 1 at some convenient frequency near the middle of the transmission range. The primary inductance L_1 can be calculated from the value 55 of C_1 and the frequency f_0 . The individual elements of the secondary circuit, L_2 and C_2 , are thereafter determined with the help of Equation 3 which takes the transformation ratio into account.

60 As an aid to performing the second design step, whereby the matching of the impedances is secured, it is of value to know the general form of the frequency characteristic of the image impedance. The variation 65 of W_b is shown in Fig. 3 in which curves a

and a' correspond to reactances, and curve b to resistive impedance. The resistive branch of the curves varies from an infinite value at each limiting frequency to a minimum value at an intermediate frequency which is generally close to f_0 . Perfect matching can not be obtained when the terminating impedance is a constant resistance but satisfactory matching is obtained when the circuit is designed so that its minimum resistance is 70 equal to the amplifier resistance R_1 . A much better result is obtained by making the minimum value of the image impedance about 75 20% smaller than the amplifier resistance, thereby securing exact equality at two frequencies near the limiting frequencies and reducing the disparity to a small amount at all frequencies except those very close to the limits.

The optimum value of the amplifier resistance in relation to the image impedance is indicated roughly by the horizontal line CC' in Fig. 3.

The following explicit formulæ, giving the circuit element coefficients directly in terms 90 of the limiting frequencies, may be developed from Equations 2, 3, and 4:

(1) coefficient of coupling

$$k = \frac{f_2^2 - f_1^2}{f_2^2 + f_1^2}; \quad 95$$

(2) resonance frequency

$$f_0 = \frac{\sqrt{2}f_1 f_2}{\sqrt{f_1^2 + f_2^2}}; \quad 100$$

(3) minimum value of W_a , denoted by $W_{a,m}$

$$W_{a,m} = \sqrt{\frac{L_1}{C_1} \times \frac{f_0}{f_2 - f_1}}; \quad 105$$

(4) primary inductance

$$L_1 = \frac{W_{a,m}}{2\pi f_0} \times \frac{f_2 - f_1}{f_0}; \quad 110$$

(5) primary capacity

$$C_1 = \frac{1}{2\pi (f_2 - f_1) W_{a,m}}; \quad 115$$

(6) secondary inductance

$$L_2 = L_1 \times \frac{R_2}{R_1} = L_1 \times \frac{C_1}{C_2}$$

In the preferred form the capacity C_2 is provided by the effective input capacity of 120 amplifier 2 and the self capacity of coil L_2 . This capacity is likely to be slightly variable with frequency because the input capacity of the amplifier is dependent upon the value of the load impedance in the amplifier output 125 circuit and to keep the variation a minimum it is necessary that the load impedance in the amplifier output circuit be fairly constant throughout the free transmission range. When a number of amplifiers are connected 130

in tandem and coupled together by circuits of the type described, the load impedances of the successive stages, by virtue of the design procedure, are sufficiently constant to make the variation of the input capacity negligibly small throughout the important range. The characteristic of the actual input impedance of the network, as measured at terminals A and B with terminals C and D closed through resistance R_2 , is shown in Fig. 4, in which the dotted line represents the reactance component and the continuous line the resistance component. The resemblance between Figs. 3 and 4 is noticeable, this being due to the substantial elimination of reflection losses by the design proportions. The substantial uniformity of the impedance throughout the transmission band is also noticeable.

From Equation 3 it is seen that the impedance transformation ratio is equal to

$$\frac{C_1}{C_2}$$

and hence that the voltage transformation ratio is equal to

$$\sqrt{\frac{C_1}{C_2}}$$

Since C_1 is fixed by the band width and the specified value of the input image impedance it follows that the minimum obtainable value of C_2 determines the maximum obtainable transformation ratio. Hence by constructing the secondary winding of the transformer so that it resonates at the proper frequency when connected to the input terminals of the succeeding amplifier, the maximum possible voltage transformation is obtained. It is to be noted that the capacity C_1 , and hence the impedance transformation is inversely proportional to the frequency band width, and also that it is independent of the location of the band in the wave spectrum.

The transmission characteristic of the coupling system is shown in Fig. 5, the curve representing the variation with respect to frequency of the gain or amplification, which is arbitrarily defined in this case as the logarithm of the ratio of the voltage between the output terminals CD to the voltage E_1 generated in the space path of amplifier 1. This curve is typical of the uniformity that has been obtained in circuits constructed in accordance with the invention.

The invention finds application particularly in amplification systems designed to amplify selectively waves of a relatively wide range of frequencies. For example, in radio telephone receiving systems of the superheterodyne, or successive detection type it may be applied to the amplification of the intermediate frequency waves. In systems of this type the invention provides for uniform amplification of a band of waves usually about 10,000 to 15,000 cycles in width and

located at a mean frequency in the neighborhood of 50,000 cycles, at the same time other frequencies are suppressed, and a substantial voltage transformation of four or five times can easily be obtained in each inter-stage circuit. Other applications of the invention may readily be perceived.

What is claimed is:

1. In combination with a pair of unequal terminal impedances, a coupling network comprising two electrically coupled anti-resonant circuits tuned to the same frequency and connected respectively in shunt to said terminal impedances, the coupling of said circuits being proportioned to provide free transmission for waves of a substantial band of frequencies between preassigned limiting frequencies f_1 and f_2 , centered about the common anti-resonance frequency, and the inductance L and capacity C of each of said circuits being related in accordance with the formula

$$W = \sqrt{\frac{L}{C} \cdot \frac{f_0}{f_2 - f_1}}$$

in which W is substantially equal to the associated terminal impedance, and f_0 denotes the common anti-resonance frequency, whereby substantially uniform transmission is provided throughout the selected frequency range.

2. An amplifier system comprising two three-electrode space discharge amplifiers and a frequency selective network adapted to connect said amplifiers in tandem, said network comprising an anti-resonant circuit included in a circuit between the anode and the cathode of the first of the tandem connected amplifiers, and a second anti-resonant circuit included in a circuit between the control electrode and the cathode of the second amplifier, said circuits being tuned to the same frequency and having a degree of coupling to provide free transmission for waves of a substantial band of frequencies, between preassigned limiting frequencies f_1 and f_2 , centered about the common anti-resonance frequency, the inductance L and the capacity C of the first of said circuits being related by the formula

$$W = \sqrt{\frac{L}{C} \cdot \frac{f_0}{f_2 - f_1}}$$

in which W is substantially equal to the space plate resistance of the first amplifier, and f_0 denotes the common anti-resonance frequency, and the inductance of the second tuned circuit being large in comparison with that of the first tuned circuit whereby a step up voltage transformation is effected.

In witness whereof, we hereunto subscribe our names this 12th day of November, A. D. 1925.

HORACE WHITTLE.
ARTHUR J. CHRISTOPHER.
